UNITED STATES PATENT OFFICE.

FRANCISZEK Klaput, of WOODLAWN, PENNSYLVANIA.

BREECH-LOADING ORDNANCE.

1,217,959.

Specification of Letters Patent.

Patented Mar. 6, 1917.

Application filed June 15, 1916. Serial No. 103,894.

To all whom it may concern:

Be it known that I, FRANCISZEK Klaput, a subject of the Emperor of Austria-Hungary, residing at Woodlawn, in the county of Beaver and State of Pennsylvania, have invented certain new and useful Improvements in Breech-Loading Ordnance, of which the following is a specification.

This invention relates to new and useful improvements in breech-loading ordnance.

The primary object of the invention is the provision of a breech-loading ordnance or cannon arranged with a retractable resiliently mounted member and a firing device whereby a projectile may be positioned within the cannon and retained in place until the firing means is released.

A further object of the invention is the provision of a cannon having a resiliently mounted breech block and a spring operated firing block, the said blocks being simultaneously separated from the cannon for loading purposes and separately released for contacting the cannon during the operation of the device.

A still further object is to provide a breech loading cannon having a projectile elevating means operable during the release of the breech block and having a firing block tensioned during the closing of the breech block whereby a release of the firing block operates the cannon.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views:

Figure 1 is a side elevation of the device partially in vertical section in its set position.

Fig. 2 is a top plan view thereof with the breech block in its open position.

Fig. 3 is a transverse sectional view taken upon line III—III of Fig. 2.

Fig. 4 is a top plan view of a portion of the device, parts being shown broken away and arranged in their fired positions.

Fig. 5 is a perspective view of the breech block detached, and

Fig. 6 is a similar view of the firing block.

Referring more in detail to the drawings, a cannon mount 10 is illustrated as arranged upon ground wheels 11 and having a cannon 12 centrally secured to the top thereof and provided with a breech piece 13 adapted for the reception of a cartridge or projectile such as 14 within the shouldered open end 15 thereof constituting the rear end of the bore of the cannon.

A frame 16 is mounted upon the supporting carriage 10 rearwardly of the cannon and opposite parallel guide rods 17 connect the said frame 16 with a transverse beam 18 positioned adjacent the rear end of the cannon. A breech block 19 of substantially cubical form is provided with diametrically arranged arms 20 having perforations 21 therethrough by means of which the breech block is slidably arranged upon the said rods 17, while retractile springs 22 are arranged upon the forward ends of the rods 17, being secured to the arms 20 and the beam 18. A firing pin 23 is slidably journaled centrally through the block 19 in axial alinement with the bore of the cannon 12, being normally retained rearwardly positioned by means of a spring 24 within a recess 25 of the said breech block 19 whereby the forward end of the pin 23 is maintained inwardly of the block 19 and the rear head 26 of the said pin is positioned slightly rearwardly of the rear face of the said block. The springs 22 normally maintain the block 19 in resilient engagement with the breech piece 13 of the cannon while rearwardly extending operating rods 27 are attached to the breech block arms 20 for forcibly moving the same rearwardly and holding the breech block open during the insertion of a projectile 14 within the breech piece 13 of the cannon.

A firing block 28 provided with outwardly extending spaced lugs 29 is slidably mounted upon rearwardly extending guide wires 30 carried by the breech block 19 and freely extending through perforations 31 in the central U-shaped rearward extension 32 of the cannon carriage frame 16. The firing block 28 being mounted upon the wires 30 by means of the lugs 29 is resiliently connected to the adjacent face of the breech block 19 by means of retractile coil springs 33 connecting the staples 34 in the rear face of the breech block 19 and similar staples 35 in the rear face of the firing block 28, the firing block being normally retained in reg

silient engagement with the firing pin head 26 as best illustrated in Fig. 4 of the drawings.

- With the elements in their normal positions with the breech and firing blocks forwardly arranged, a rearward pull exerted upon the setting rods 27 brings the two blocks rearwardly with the firing block 28 arranged within the rear extension 32 of the frame 16 automatically allowing a latch hook 36 to engage over a lug 37 upon the firing block thus retaining the latter in its set position while the breech block 19 is forcibly maintained rearwardly by means 5 of the setting rods 27 until the projectile 14 has been positioned within the breech piece 13 in the manner hereinafter set forth. After the projectile has been so positioned the rods 27 are released allowing the springs 20 22 to bring the breech block 19 in setting engagement with the rear face of the breech piece 15 which movement of the breech block tensions the firing block springs 33, the firing block being maintained in its rear set 25 position by means of the latch 36. A depending handle 37' is carried by the latch 36 performing the function of a trigger upon the inward movement of which handle, the latch 37 is released from the lug 37 and the springs 33 then forcibly move the firing block 28 forwardly against the head 26 of the firing pin 23, thereby projecting the pin into engagement with the cartridge 14 within the breech 13 of the cannon. The springs 35 22 being of much greater strength than the smaller springs 33, maintain the breech block 19 in its closed position while the firing block 28 is set in its retracted arrangement.
- 40 Upright U-shaped seats 38 adapted for receiving a projectile 14 are carried by transverse bars 39 of the carriage 10 in a plane beneath the plane of the cannon 12, a hoisting arrangement being provided for elevating the projectile adjacent the receiving bore opening 15 of the cannon breech piece 13. A chain 40 is detachably arranged around the projectile 14 and extends over an idler roller 41 journaled longitudinally between the frame 16 and beam 18 and is attached to a turn shaft 42 journaled longitudinally of the carriage 10 and operatively connected by suitable gearing 43 with a toothed wheel 44 arranged at one side of the gun carriage 10 and provided with a turn crank 45. When the free end of the chain 40 is secured around the projectile 14, the projectile is forcibly elevated within the members 18 by turning the crank 45 and 45 when positioned adjacent the breech block 13, the projectile may be readily inserted within the breech in its firing position as illustrated in Fig. 4 of the drawings.

From this detailed description of the invention it will be apparent that the cannon

is readily operated by setting the firing block 28 and arranging the breech block 19 in its retracted position and then positioning the projectile 14 within the cannon, after which the breech block 19 is released allowing the 70 same to position itself with the firing pin 23 engaging the projectile 14 with the firing springs 33 fully tensioned. The latch 36 is then released by the trigger handle 37 and the forcible contact of the firing pin head 26 with the firing block 28 operatively explodes the projectile 14.

Suitable connections may readily be arranged between the breech block 19 and the axle 44^a of the wheel 44 whereby the breech block is retracted simultaneously with the elevating of the projectile 14 during the turning of the crank 45 and such arrangement is included in the present invention. The provision of bands 44^b connecting the 80 breech block arms 20 with the revolving shaft of the operating wheel 44 is contemplated as furnishing such co-operating means and while the present arrangement is believed to be preferable, minor changes may 85 be made without departing from the spirit and scope of the invention as claimed.

What I claim as new is:—

1. A piece of ordnance comprising a carriage, a cannon mounted thereon, a shiftable breech block resiliently attached to the said carriage in normal contact with the breech portion of the cannon, a shiftable firing block resiliently connected to the said breech block and releasable retaining means for the firing block when in its set position. 95
2. A piece of ordnance comprising a carriage, a cannon mounted thereon and having a rearwardly arranged breech portion, guide rods upon the said carriage, a breech block slidably arranged upon said guide rods, a firing pin centrally positioned through the said block in axial alinement with the said cannon, resilient connections between the said breech block and carriage whereby the 100 said block is normally maintained in resilient contact with the said breech portion, and firing means for the said pin. 110
3. A piece of ordnance comprising a carriage, a cannon mounted thereon and having a rearwardly arranged breech portion, guide rods upon the said carriage, a breech block slidably arranged upon said guide rods, a firing pin centrally positioned through the 115 said block in axial alinement with the said cannon, resilient connections between the said breech block and carriage whereby the said block is normally maintained in resilient contact with the said breech portion, rearwardly arranged guide wires carried by 120 the said block slidably positioned through the said carriage, a firing block slidably mounted upon the said wires rearwardly of the breech block and firing pin, retractile springs connecting the said firing block and 125 130

breech block, and a releasable latch for the said firing block.

4. A piece of ordnance comprising a carriage, a cannon mounted thereon and having a rearwardly arranged breech portion, guide rods upon the said carriage, a breech block slidably arranged upon said guide rods, a firing pin centrally positioned through the said block in axial alinement with the said cannon, resilient connections between the said breech block and carriage whereby the said block is normally maintained in resilient contact with the said breech portion, rearwardly arranged guide wires carried by the said block slidably positioned through the said carriage, a firing block slidably mounted upon the said wires rearwardly of the breech block and firing pin, retractile springs connecting the said firing block and breech block, the said carriage having a rearwardly extending U-shaped central frame, within which the said firing block is arranged when in its retracted set position, an upright lug upon the said fir-

ing block, and a spring pressed trigger latch 25 carried by the said frame in engagement with the said lug when the device is set.

5. A piece of ordnance comprising a carriage, a cannon mounted thereon, a retractile breech block shiftably mounted upon the 30 said carriage, a projectile elevating means arranged laterally of the said cannon and coöperative connections between the said breech block and elevating means whereby the breech block is retracted during the operation of the said means.

6. A device of the class described, comprising a carriage, a cannon mounted thereon having a breech piece, U-shaped supports arranged beneath the plane of the said cannon, and adapted for the reception of a projectile, a winding shaft, projectile hoisting chains attached to the said shaft, and operating means for the said shaft arranged at one side of the carriage.

In testimony whereof I affix my signature.

FRANCISZEK KLAPUT.
